UNITED STATES PATENT OFFICE.

KARL A. STRITTER, OF NAHANT, MASSACHUSETTS.

SHOE.

Application filed December 7, 1928. Serial No. 324,458.

This invention primarily relates to shoes of the low cut type, generally known as slippers or pumps, and in the uppers of which various portions are cut away to reveal the 5 stocking of the wearer and to produce an ornamental effect.

The objects of the invention are to provide a shoe of the type above referred to, in which an interlaced or interwoven effect will 10 be produced in the fore part of the upper more particularly in the top portion thereof, and which may be manufactured without difficulty, and will hold its original shape and be comfortable to the foot of the wearer 15 when worn.

I accomplish these objects in the manner hereinafter described and as illustrated in the accompanying drawing in which:

Fig. 1 is a plan view of the forepart of 20 a shoe embodying my invention.

Fig. 2 is a combined side elevation and longitudinal, central, vertical section thereof at line 2—2 of Fig. 1.

Fig. 3 is a plan view of a part of the main 25 vamp portion.

Fig. 4 is a similar view of the top vamp portion.

Fig. 5 is a plan view of a modified form 30 of main vamp portion.

Fig. 6 is a plan view of the forepart of a shoe embodying a slightly modified form of 35 the invention.

My invention may be embodied in any well known type of low cut shoe having its 40 upper of leather or other suitable material. In the construction of said shoe, the forepart of the upper comprises two sections, one of which consists of a main vamp section *a*, which is directly attached at its edge to the sole, and extends continuously about the sides and tip of the forepart, the middle or top portion thereof being provided with a series of slots *b*, which extend rearwardly from the tip portion, at an approximately U-shaped line, which, in a general 45 way, corresponds to the outline of the toe portion of the sole, said slots being preferably tapered in width from their front ends and terminating in slits, thereby forming a series of straps *c*, which extend convergently, as they extend rearward, so that their edges may be held in contact at their ends. Said straps are preferably symmetrically arranged, for the sake of appearance, with relation to the longitudinal center line of the 50 shoe.

The other section of the forepart consists of a top, or saddle section *d*, the edge of which is shaped to extend along a line parallel to the line of the front ends of the slots *b* and is provided with a series of openings, preferably in the form of transverse slots *e* which form transverse straps *f*, said slots and straps being preferably of approximately the same width as the straps *c* and the 60 ends of the slots *e* being terminated in a line which is adapted to coincide approximately with the line of the ends of slots *b*, when in position thereon.

In assembling said sections *a* and *d* the section *d* is stitched to the section *a* in a position in which it slightly overlaps the latter beyond the line of the front end of the slots *b* and the ends of its slots *e* are approximately in coincidence with said line, as 70 shown in Figs. 1 and 2. The longitudinal straps *c* are then interwoven with the transverse straps *f*, in ordinary basket weave fashion, and the ends of the straps *c* are stitched, with their edges in contact, to the 75 wider end of a triangular shaped tab or connecting piece *g*, the opposite or narrower end thereof having a loop *h* therein, thru which a shoe securing strap *i* is passed, so that when the strap *i* is secured, it will act 80 to pull on the straps *c*, or resist strain thereon and all parts will be drawn closely to the foot of the wearer and will be thus securely held in position.

The straps *c* are preferably formed continuously with the material of which the main vamp section is formed, so that the interior of the shoe is as smooth as it would be with any single piece vamp and no discomfort to the wearer will be caused by the 90 formation of a shoulder on the interior of the shoe, but the same result may be secured, so far as the comfort of the wearer is concerned, by means of the construction shown 95 in Fig. 5, in which the main vamp section *j* is cut out at its middle portion along a 100 U-form line, and a separate piece *k* is provided, having one edge butted with the edge portion formed along said line and stitched thereto by cross stitches, the opposite portion of the set-in piece *k* being slotted to provide straps *m*, similar to the straps *c*. Otherwise the construction is similar to that before described. The principal advantage 105 of this construction is that it enables the use of different material for the longitudinal straps from that from which the main vamp 110

section is formed, so that different color effects may be produced. Also a saving may be made in the material used.

In Fig. 6, the application of the invention 5 to a "pump" type of slipper is shown, as distinguished from the type having a shoe securing strap which extends over the instep.

In this construction, the longitudinal straps which extend from the toe portion of 10 the main vamp section are interwoven or interlaced with the top section, as before described and then end portions thereof are stitched directly to a cross strap *n* which, as shown, is approximately parallel to the 15 straps of the top section and is attached at its ends in a position to form the front portion of the foot opening of a shoe of the "pump" type. With this construction, the strap ends are securely attached and, as a 20 result, a construction is produced which has practically the stability of a single piece vamp.

With the above described constructions, while the ultimate purpose is to secure a shoe 25 having an ornamental or attractive appearance, it has other advantages in a more practical way, in that a comfortable warm weather shoe is produced, as ventilating openings are provided over the top of the forepart, 30 and, while the straps are securely held at their ends, their intermediate portions are free to move laterally to some extent, so as to conform readily to the foot of the wearer.

I claim:

35 1. A shoe upper comprising a main vamp section arranged to extend about the side and tip portions of the shoe fore part and having a series of straps extending longitudinally rearward from its tip portion, a 40 top section disposed on, and attached at its edge portion to said main section adjacent the portion from which said straps extend, said top section having openings with which said straps are interwoven, and a trans- 45 versely extending shoe securing strap and means connecting the rear ends of said longitudinal straps thereto.

2. A shoe upper comprising a main vamp section arranged to extend about the side portion of the shoe forepart and having a 50 series of straps extending longitudinally rearward from its tip portion, a top section attached at its edge portion to the adjacent portions of said main section and transversely slotted between its side edge portions, forming straps with which said longitudinal straps are interwoven, a shoe attaching strap and means connecting the rear ends of said longitudinal straps thereto. 55

3. A shoe upper comprising a main vamp 60 section arranged to extend about the side and tip portions of the shoe forepart, and having a series of straps extending rearwardly from its tip portion, said straps being separated by slots which terminate at 65 their front ends in an approximately U-shaped line, a top section, which overlaps said main section beyond said line and is attached thereto adjacent said line, said top section being transversely slotted between its side edge portions to form straps 70 which are interwoven with said longitudinal straps, a shoe-attaching strap, and means connecting said longitudinal straps thereto at their ends. 75

4. A shoe upper comprising a main vamp section arranged to extend about the side and tip portions of the shoe forepart and having a series of slots therein which extend rearwardly from its tip portion to 80 form a series of straps which extend continuously therewith, said slots being terminated at their front ends in an approximately U-shaped line, a top vamp section overlapping said main section beyond 85 said line and stitched thereto, said top section being transversely slotted to form straps which are interwoven with said longitudinal straps, and a shoe attaching strap connected to the ends of said longitudinal 90 straps. 95

In testimony whereof, I have signed my name to this specification.

KARL A. STRITTER.
